CLAIM

The ornamental design for a laptop sleeve, as shown and described.

DESCRIPTION

FIG. 1 is a perspective view of a laptop sleeve showing my new design, shown in a closed position;

FIG. 2 is a perspective view of the laptop sleeve shown in an open position;

FIG. 3 is a front elevational view of the laptop sleeve shown in FIG. 1;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict stitching and form no part of the claimed design.
